UNITED STATES PATENT OFFICE

GEORGE T. MOTT, OF PEARL RIVER, NEW YORK

APPARATUS FOR HEAT EXCHANGING

Application filed February 12, 1927. Serial No. 167,684.

The invention relates generally to heat exchangers, and is more particularly directed to the tubes used in said heat exchangers as heat transfer surfaces between the heat containing and heat absorbing agents and through which tubes one of said agents flows.

An object of the invention is to provide an improved tube element, particularly for heat exchangers, whose parts shall be so fashioned, arranged and combined that frictional resistance to the flow of a fluid therethrough, as a heat agent, shall be reduced to a minimum and the evils consequent upon such frictional resistance correspondingly obviated.

Another object of the invention is to make such a tube element capable of receiving at its entry port fluid in quantity sufficient to utilize the full capacity of the tube element.

Other objects of the invention are to provide a tube element of the character described which shall be simple and economical in construction; easily installed and conveniently accessible; whose parts may be easily removed and replaced or duplicated; and one of the parts of which shall be adapted for cleaning part of the tube element proper. These and other objects of the invention will be more fully set forth in the following description.

In the accompanying drawings which are referred to herein and form part hereof,

Fig. 1 is a longitudinal section of part of a heat exchanger in which is employed and shown tubes constructed in accordance with the invention and which form the heat transfer surfaces of the heat exchanger;

Fig. 2 is a view in cross-section taken on the line 2—2 of Fig. 1, showing the relationship of the inner and outer tubes of Fig. 1 and the tube-supporting members;

Fig. 3 is an enlarged view, parts being broken away, in longitudinal section of an inner and outer tube shown in Fig. 1 and showing the same more in detail;

Fig. 4 is a similar view taken on a plane at right angles to the plane of the section shown in Fig. 3;

Fig. 5 is a longitudinal section of part of a tube element and shows the same arranged

for a reverse flow of the heat agent used therein;

Fig. 6 is a longitudinal section of an end of an inner tube used in the device, showing details, and is also taken on a plane at right angles to the plane of the section shown in Fig. 3;

Fig. 7 is a view, partly in elevation and partly in cross-section, taken on the line 7—7 of Fig. 6;

Fig. 8 is a similar view taken on the line 8—8 of Fig. 3;

Fig. 9 is a perspective view showing in detail the retaining members shown in Fig. 1;

Fig. 10 is a sectional view of the end of a tube of the art, illustrating the flow of a stream of liquid into the tube; and

Fig. 11 is a perspective view, parts being broken away, of an end of a tube constructed in accordance with the invention and illustrating the flow of a stream of liquid into the same.

Referring to the drawings in detail, there is illustrated therein a preferred embodiment of the invention as used in a heat exchanger of the type shown in my co-pending application, Serial No. 127,039, filed August 4, 1926, and which need not be described in detail herein. Said heat exchanger consists generally of a vapor chamber 15 formed with a cylinder shell 16, having heads 19 and 20 and provided with the usual vapor flow ports, not shown. At one end of said vapor chamber 15 and spaced apart therefrom so as to provide an air gap between them is arranged a container 26 divided by a partition wall 29 into receptacles 39 and 40 which are provided with inlet and outlet ports not shown. One of the heat agents, as for example, oil, enters the receptacle 39 and then the tubes 61. These tubes lead from said receptacle 39 and, passing through the receptacle 40, project into the outer tubes 53. These latter tubes 53 lead from the receptacle 40 and, traversing the space between the container 26 and the vapor chamber 15, project into the vapor chamber 15 through the head 19. The closed ends of the tubes 53 are freely supported on curved supporting members 54^a, see Fig. 9, preferably cast integrally with the

head plate 20. As shown, these supporting members 54^a are arc-shaped and are employed, four to each tube end, with space between each two arc members. Further reference will be made to these supporting members. The supported ends of the tubes 53 are sealed with plugs 55^a, preferably screwed into the ends of the tubes. It will be seen that the oil entering the tubes 61 will pass therefrom at their extreme inner ends into the outer tubes 53 and, abruptly changing the direction of flow, pass through said outer tubes 53 into the receptacle 40, absorbing in its passage the heat from the heat-containing vapor in the vapor chamber 15. It is with these tubes and their associated parts that this invention is more particularly concerned. A description of the foregoing circulation tubes and parts will be sufficient for an understanding of the present invention. And here it may be noted that the direction of flow of the heat agent, as oil, through the tubes may be reversed and flow, first, through the outer tube and thence into and through the inner tube. Also, the heat exchanger may be used so that the heat-containing agent flows through the tubes while the heat-absorbing agent is in the chamber 15.

It is to be observed that a sharp-edged tube orifice, when used as an entry port, will subject the entering liquid to jet contraction, and it is the contracted cross-sectional liquid area at this point, rather than the actual cross-sectional area of the tube which determines the capacity of this tube element. After passing the area of contraction, and because of frictional resistance which causes a slowing up of the liquid flow, a liquid expansion occurs which fills the entire tube but at a velocity incident to the quantity which it is possible to pass through the contracted area. It will be obvious that this reduced flow implies a mechanical capacity loss of great relative dimensions, and particularly in a heat exchanger where thermal efficiency demands a high velocity.

According to one feature of the invention, therefore, an entry port is provided for the tube through which the heat agent or liquid enters the tube element, which port shall be capable of admitting liquid to the tube proper in volume equal to the full capacity of the tube, and which port preferably, shall not involve any change in the tube structure which would render the tube unfit for use with certain desirable associated parts.

In this connection it is to be noted that the flow of liquid into a tube at a velocity sufficient to induce a contracted area with an adjacent expanded liquid area will cause the liquid to form a closed annular space around the small diameter of the liquid column at the point of contraction and that the constant drag by the flowing liquid on the atoms of air in the enclosed space will have a tend-

ency to rarefy the air body and thus cause a partial vacuum. The improved entry port, therefore, provides for filling this annular air space and presenting at this point of contraction a coherent, liquid body equal to the full capacity of the tube and maintaining this coherent, efficient flow throughout the tube element. As shown, see Figs. 1, 3 and 6, the peripheral wall of the tube is formed with a serrated edge forming extended tongues 63 with intervals of space between them, and the entering liquid stream is admitted to the tube at different intervals and entry planes about and between the tongues. There will yet be a tendency to form the area of contraction at the lower edges or lowest entry point in the said serrated edge but in a reduced dimension. Flowing down the extended tongues 63 of the tube end and at the point of contraction will be integral streams of liquid which will have previously met all frictional entry demands upon them, these streams alternating with voids 64 formed between and at the bases of the said extended tongues 63, see Fig. 11, and thus entering the operative portion of the tube at intervals. The immediate effect at these voids 64 is to draw the liquid of the two adjacent liquid streams from the tongues on both sides of the valleys in parallel, vertical, transverse, and diagonal streams into the voids and fill them and thus form an integral liquid body or column equal to the full capacity of the tube and maintaining this integral efficient flow throughout. It will be seen that the serrated edges by increasing the length of flow line decrease proportionately the velocity of the immediate entry flow and thus cause a reduction in total frictional head and provide for a full capacity stream. It will also be seen that an entry port formed as thus described will interpose no obstacle to the use of any desired associated parts with the tube. As shown, for instance, see Fig. 6, the gland 63^a may be used, the same fitting tightly over the stuffing 63^b. And it is pointed out that when the direction of the flow is reversed and the heat agent enters the outer tube 53 first and then flows from the tube 53 into the inner tube 61, the entry port of the tube 53 may be fashioned as above described in connection with the entry port of the tube 61, or as shown.

A defect common to the double tube elements of the art for heat exchanger service lies in the fact that, where the tubes are of equal cross-sectional area and of similar cross-sectional contour, the liquid in the outer tube is of so thin a stream that the adhesion of the liquid to the peripheral walls of the surrounding tubes will be so great as materially to obstruct the flow. Particularly is this true of liquids of high viscosity. This lack of capacity of the outer tube is caused not by the lack of space between the inner and

outer tubes but by inefficient outlining of the same. Both tubes being similar in cross-sectional contour, the space between the inner and outer tubes may be equal to the space within the inner tube and yet, as will be seen, because of the space between the tubes being defined by the annular ring formed by the outer tube around the inner tube, the compact stream of liquid issuing from the inner tube will, when diverted into the outer tube, be expanded into the thin stream above referred to which will unduly adhere to the peripheral walls of the surrounding tubes.

According to another feature of the invention, therefore, the inner and outer tubes are relatively so formed, as in cross-sectional contour, that ample space will be afforded between the inner and outer tubes for the passage therethrough in an even, continuous flow, and with undiminished velocity, of the liquid issuing from the inner tube 61 into the outer tube 53. For example, one of said tubes, preferably and as shown, see Figs. 4 and 7, the inner tube 61, is contracted on one diameter, forming long sides 66, and expanded on another diameter, forming short sides 67, so as to approach in cross-sectional contour an oval formation, while the other or outer tube 53 may assume such cross-sectional contour as will provide enlarged spaces. It will be seen that the large spaces 68, thus provided between the tubes on the opposite ends of the minor axis of the inner tube, provide severally for easy flow of the entire liquid stream issuing from the inner tube, reduced adhesion of the liquid to the surrounding tube walls, and reduced frictional effect. Also, because of said large spaces 68 the abrupt change of direction of the flow of the liquid is rendered easier. Furthermore, the frictional resistance of the liquid being reduced, the raising of temperature caused by said frictional resistance is also eliminated and with it the many and serious evils attendant thereon.

It is pointed out that in constructions of the art the liquid in passing from an inner to the outer tube makes a short, sharp turn with the result that the even continuity of the flow is broken, the speed diminished by increased frictional resistance, and erosion of the outer tube is promoted by the continual sharp impacts of the liquid against said tube. Further to assist in maintaining an even, continuous flow of the liquid stream, therefore, and according to another feature of the invention, a diverging block or deflector 69 is provided in the outer tube 53 adjacent the inner end of the inner tube 61, see Figs. 3 and 4. This block or deflector 69 is arranged in place in the inner tube 61 in any suitable manner. As shown, it is fastened by means of lugs 70 extending, one on each side, from the end of said inner tube 61, and lifting into suitable recesses, one in

each side of said block. An end 71 of each lug 70 is turned and fits into another suitable recess in said block and additionally the lug is fastened to the block with a screw 72. The diverging block or deflector 69 fits snugly 70 into the outer tube 53 and is formed with relatively sharp peripheral edges 73 made necessary by the requirements for a smooth surface and a low resistance effect. Said block or deflector 69 is formed with an end 75 dished out or recessed on each side of a median line, forming a sharp edge 74, extending across the end of the block. On each side of this sharp median edge 74, the oppositely curved faces 76 and 77 of each recess diverge from said median edge in such manner as to provide at every point throughout each entire face the exact angle of divergence for a liquid of any given viscosity, and for the diameter of any particular turn or diversion. It will be seen that the liquid stream, following these curves, first in one direction towards the end of the outer tube and then swerving swiftly but gradually in the reverse direction will make the desired change 80 in flow without impairing the even, continuous flow of the liquid and without checking its speed and without injuring the walls of the tubes. It is to be noted also that these diverging blocks may be formed with their 85 curved faces 76, 77 in variable form on opposite sides of the recessed portion of the block or deflector so that the liquid may flow from the outer tube to the inner tube in the same even, continuous flow and without impairment of speed. It is pointed out that the block or deflector 69 is so positioned with relation to the end of the inner tube 61 that the full volume of liquid will be permitted to flow from one tube to the other normally uninfluenced by the frictional resistance to such a change of direction, this being effected by the position and variable curvature of the deflecting faces. It is to be understood that the deflecting blocks will vary in structure 90 and curvature to meet the requirements for all gases and fluids or liquids in accordance with their temperatures, vapor contents or viscosities.

As has been stated, the block or deflector 95 69 is formed with relatively sharp edges which are continuous around the outer limits on both sides and serve the additional purpose of tube cleaning, both when entering the tube and when removing for repairs or 100 other reasons. The block is further formed with a threaded orifice 78 so that a pipe or rod may be applied for direct cleaning. It will be noted also, see Fig. 3, that a space 79 is afforded in the outer tube between said 105 diverging block or deflector 69 and the sealing plug 55^a at the end, if desired, or said block and plug may be made integral.

Referring to the supporting members 54^a for the ends of the tubes, it is to be noted that 110

they are formed in segments to prevent the distortion under high temperature incident to arc members of greater dimension.

The invention in its broader aspects is not limited to the precise construction shown and described, nor to any particular construction by which the same may be carried into effect, as many changes may be made in the details thereof without departing from the main principles of the invention or sacrificing its chief advantages; nor is the invention limited to a heat exchanger devoted to any particular use.

I claim:

1. A friction-reducing circulating unit for heat exchangers and the like including in combination, a pair of tubes, one projecting into the other, and a deflector in an end of the outer tube and associated with the inner end of the inner tube, said deflector being divided by a central sharp edge and diverging therefrom into curved recesses.

2. A friction-reducing circulating unit for heat exchangers and the like including in combination, inner and outer tubes and a removable deflector arranged in the outer tube, said deflector presenting to the adjacent end of the inner tube a sharp outer edge from which extend recesses to a median line, the faces of said recesses being curved to provide for the liquid stream flowing from the inner tube into the outer tube at the exact angle of divergence for a liquid of a given viscosity, and for any given diameter of diversion, whereby the liquid will flow from the inner tube into the outer tube in an even, continuous flow.

3. A friction-reducing circulating unit for heat exchangers and the like including in combination, inner and outer tubes, and a removable deflector arranged in the outer tube and presenting to the adjacent end of the inner tube a sharp outer edge from which extend recesses to a median line, the faces of said recesses being curved to provide for the liquid stream flowing from one tube into the other tube at the angle of divergence for a liquid of a given viscosity and for the diameter of the diversion, whereby the liquid will flow from one tube to the other tube in an even, continuous flow.

4. A friction-reducing circulating unit including in combination, inner and outer tubes, the inner tubes being substantially oblong in cross-sectional contour, and the outer tube being substantially circular in cross-sectional contour, and the flow axes of said tubes being substantially parallel thruout the length of said inner tube.

5. A friction-reducing circulating unit including in combination, inner and outer tubes, one of said tube being substantially oblong in cross-sectional contour, and the other tube being substantially circular in cross-sectional contour, and the flow axes of said tubes

being substantially parallel thruout the length of one of said tubes.

6. A friction-reducing circulating unit including in combination, an outer tube and an inner tube contracted on one diameter and expanded on the other, and the flow axes of said tubes being substantially parallel thruout the length of said inner tube.

7. In or for a friction-reducing circulating unit for heat exchangers and the like a deflector presenting a face adapted to divert the flow of a liquid stream, the perimeter of said face having a sharp edge.

8. In or for a friction-reducing circulating element for heat exchangers and the like a deflector presenting a face adapted to divert the flow of a liquid stream, the perimeter of said face having a sharp edge and the face on the reverse of said deflector also having its perimeter formed with a sharp edge.

9. A friction-reducing circulating unit including in combination, an outer tube, and inner tube, one of said tubes being contracted on one diameter and expanded on the other, and the flow axes of said tubes being substantially parallel thruout the length of said inner tube.

10. A friction-reducing circulating unit for heat exchangers and the like including in combination, an outer tube, an inner tube, one of said tubes being contracted on one diameter and expanded on the other, and a deflector arranged in said outer tube and associated with said inner tube, said deflector presenting curved faces to the fluid stream flowing from said inner tube.

11. A friction-reducing circulating unit for heat exchangers and the like including in combination, a tube, a removable plug arranged at one end thereof, and a removable deflector arranged in said tube, whereby said plug can be removed to permit ready insertion or removal of said deflector into or from said tube.

12. A friction-reducing circulating unit for heat exchangers and the like including in combination, a pair of tubes, one projecting into the other, the outer end of the inner tube being formed with extending arc-shaped tongues and arc-shaped valleys at the bases of and between said tongues, and a deflector arranged in said outer tube and associated with said inner tube, said deflector presenting curved faces to the fluid stream flowing from said inner tube whereby said stream will pass thru said unit in an even, continuous flow in volume equal to the full capacity of the tubes.

13. A friction-reducing circulating unit for heat exchangers and the like including in combination, a pair of tubes, one projecting into the other, an open end of one of said tubes being formed with extending arc-shaped tongues and arc-shaped valleys at the bases of and between said tongues, and a de-

5 reflector arranged in the outer of said tubes adjacent the inner end of the inner tube, said deflector presenting curved faces to the fluid stream flowing from said tube with the arc-shaped tongues to the other tube, whereby said stream will pass thru said unit in an even, continuous flow in volume equal to the full capacity of the tubes.

- 10 14. A friction-reducing circulating unit for heat exchangers and the like including in combination, a pair of tubes, one projecting into the other, an open end of one of said tubes being formed with extending arc-shaped tongues and arc-shaped valleys at the bases of and between said tongues, one of said tubes being contracted on one diameter and expanded on the other, and a deflector arranged in said outer tube and associated with said inner tube, said deflector presenting 15 curved faces to the fluid stream flowing from the tube with said arc-shaped tongues to the other tube, whereby said stream will pass thru said unit in an even continuous flow in volume equal to the full capacity of the tubes.
- 20 25. In testimony whereof, I have affixed my signature hereto.

GEORGE T. MOTT.
